PORTABLE LIFTING DEVICE

Abraham Landskroner and Samuel Landskroner,
Baltimore, Md.

Application October 22, 1956, Serial No. 617,331

5 Claims. (Cl. 212—71)

This invention relates to lifting devices, and more particularly to a portable lifting device or hoist which can be utilized for lifting objects through windows, from and into trucks, and the like.

For a long time there has been a long felt need for a portable lifting device or hoist which can be utilized effectively and efficiently for lifting and moving objects of various sizes and shapes through a window from or to a street, or in moving objects from or to a truck or freight car, to name only a few uses of such a device. Most of the lifting devices, hoists, derricks that have been developed in the past are cumbersome, difficult to assemble and disassemble, and are not efficient and reliable in operation.

It is one of the objects of this invention to provide a novel lifting device which can be used effectively and efficiently to lift and move objects of various sizes and shapes.

Still another object of this invention is to provide a portable lifting device or hoist which can be utilized under varied conditions to effectively and efficiently lift loads of various weights and sizes.

And still another object of this invention is to provide a portable lifting device or hoist which is economical to manufacture, efficient and reliable in operation, and which is easy to install, maintain, and disassemble.

And even still another object of this invention is to provide a portable lifting device or hoist which may be easily applied to a window casing to lift heavy objects through a window above street level.

To provide a portable lifting device which is compact and easy to assemble and disassemble, are other objects of this invention.

Still another object of this invention is to provide a lifting device which can be readily adjusted to fit windows of various sizes.

To provide a portable lifting device which can be rapidly removed from one window and installed in another window with a minimum of effort, is still another object of this invention.

Still other objects of this invention are to provide lifting devices or hoists which are rugged, sturdy, and which will take a great deal of punishment without damage thereto.

To provide a portable lifting device which can be used in conjunction with a track and carriage to move objects of various sizes and shapes, is even still another object of this invention.

These and other objects and advantages of this invention will become more apparent from the following description and drawings in which:

Fig. 1 is a side elevation of the portable lifting device comprising this invention mounted in an operative position in a window;

Fig. 2 is a front elevation of the portable lifting device shown in Fig. 1 without the block and tackle;

2

Fig. 3 is a longitudinal section taken along line 3—3 of Fig. 1;

Fig. 4 is a longitudinal section taken along line 4—4 of Fig. 1;

5 Fig. 5 is a modification for the arrangement for clamping the device to a window;

Fig. 6 is a side elevation of a second embodiment of the portable lifting device comprising this invention, illustrating the device in conjunction with a track and carriage;

10 Fig. 7 is an end view of a portion of the portable lifting device illustrated in Fig. 6;

Fig. 8 is a cross section taken on line 8—8 of Fig. 6; and

15 Fig. 9 is a cross section taken on line 9—9 of Fig. 6.

Referring now to Figs. 1 to 5 of the drawings, there is illustrated one embodiment of the invention comprising a portable lifting device or hoist 11 for moving objects of various sizes and shapes from or into a building through a window 10 installed in a wall 12. It is to be noted that this invention is not limited to lifting loads through windows, because it can be readily adapted to a wide variety of other uses where it is desired to move heavy loads. The window 10, as shown in Figs. 1 and 2, 25 consists of a stool 10, a head 16, and window guides 18.

The lifting device 11 consists of two main metal members 20, preferably of tubular cross section, having a top angular portion 28 formed integral with members 20. The two main members 20 have two base members 22 which are mounted concentrically therewith at their lower ends. These members 22 will be described more in detail subsequently.

In addition, the lifting device 11 consists of a cross member 24 which is fastened to and pivoted at point 52 to a member 62. Member 62, in turn, is welded to the upper end of the top angular portion 28 of tubular members 20. As shown best in Fig. 1, a second member 54 is secured by welding or the like to the top angular portion 28 of the main members 20 and it extends outwardly and substantially in line with cross member 24 and member 62. This member 54 has an aperture 56 in its outermost end for receiving a block and tackle arrangement 70.

As seen best in Figs. 1 and 3, the innermost end of cross member 24 is provided with an elongated collar 48. This cross member 24 has a head 50 secured thereto to prevent the cross member 24 from slipping out of the collar 48. A top base support 42 is used for holding the cross arm 24 in position at the head 16 of the window 10. The lower end 66 of the top base support 42 has an aperture or opening provided therein for receiving and supporting the collar 48 of the cross member 24. The collar 48 as well as the cross member 24 are secured in operative position by set screws 46 received in a threaded aperture 68 in the lower end 66 of the base support 42. The top base support 42 is provided with a felt member 44 to prevent the apparatus from injuring the wall 12. The top base support 42, therefore, is used to support the portable lifting device or hoist 11 against the head 16 of the window.

Two cross support members 26 are secured to the collar 48 and the two main members 20. The ends of the cross members 26 are secured to welded rings 58 and 60 on the main members 20 and collar 48, respectively. These cross support members 26 are utilized to add rigidity to the portable lifting device or hoist 11.

Referring now to Figs. 1, 2 and 4, the lower ends of the main support members 20 are provided with concentric base members 22. At the upper end of each base member 22, there is provided a collar lock 34. In addition, a collar lock 38 is provided on each main mem-

ber 20 next to the collar lock 34. A threaded aperture 64 is formed in collar lock 34, and it receives a screw 36 for locking collar lock 34 to the base member 22. In addition, collar lock 38 is provided with a screw 40 for locking collar lock 38 to the main member 20. A series of threaded apertures can be provided in members 20 and 22 for receiving the screws for securing the collar locks 34 and 38 in various positions along the members 20 and 22.

Referring now to Fig. 5 of the drawings, there is shown a modification of the arrangement for clamping the portable lifting device or hoist 11 to the window. In addition to the fixed top base support 42, a sliding clamp 72, having a finger or arm 74 and an enlarged apertured portion 75, can be used to help secure the device to the head 16 of the window 10 and the wall 12. In this arrangement, a plurality of apertures 78 are provided in the cross member 24 for receiving screws 76 mounted in the enlarged apertured portion 75. Thus, the cross member 24 can be adjustably secured to various size windows.

The lower end of each base member 22, as shown best in Figs. 1 and 2, is provided with a base support 30 including a toe 32 for positioning the base supports against the stool 14 of the window 10. By means of this arrangement, the portable lifting device or hoist 11 is prevented from slipping from the stool 14 of the window.

Referring now to Figs. 6 to 9, there is illustrated a modified form of the invention wherein two portable lifting devices 11 are utilized, one on the outside of the window 10 and the other on the inside of the window, for both lifting a heavy load and for moving the heavy load through the window to the inside of the building. In this arrangement, two identical frameworks A and B, as previously described in connection with the embodiment of the invention in Figs. 1 to 5 are used, except for the elimination of the following components, namely the cross support members 26, the welded rings 58 and 60, the extension member 54, and the cap 50 from the cross member 24.

As best seen in Fig. 6, the rod 24 is extended through the collar 48 so that it can be secured at point 52 to the welded member 62 of the upper end of the top angular portion 28 of the main members 20, corresponding to the device A. In addition, two top base supports 42 are used to support the collar 48 as previously described, one in the inside of the window 10 and the other on the outside of the window.

Below the cross arm or member 24, there is positioned a T-track or bar 80 which has mounted thereon a carriage 82 having wheels 84, as best seen in Figs. 6 to 9. These wheels 84 ride on a flange 98 of the T-bar 80. The carriage 82 is provided with screws 86 to hold the block and tackle 70 to the carriage. Each end of the T-bar 80 is provided with end members to prevent the carriage 82 from rolling off of the track or bar 80.

A plurality of brackets 90 are provided on the cross member 90 to hold the T-bar 80 in an operative position. These brackets 90 are secured at their lower ends to the T-bar 80 by suitable screws 92. In addition, the top base supports 42 are provided with extensions and these extensions are secured to the T-bar 80 by screws 96.

In actual operation, either embodiment of the portable lifting device 11 is mounted in a window, as previously described, and the desired load is secured to the block and tackle arrangement 70. The load is lifted by the block and tackle arrangement 70 to the proper height, and then it is taken by hand from the arrangement or it is moved into the building by the arrangement as described in connection with Figs. 6 to 9.

The various parts can be manufactured of light weight metal, such as aluminum, or heavier metal, such as steel.

Obviously many modifications and variations of the present invention are possible in light of the above teachings. It is, therefore, to be understood that within the scope of the appended claims the invention can be practiced otherwise than as specifically described.

What is claimed is:

1. A lifting device, comprising, structure defining at least two telescopic frameworks, each said framework including a pair of spaced legs with a V-shaped section secured to the upper ends of said pair of legs, means including a cross member having its ends secured to the upper ends of said V-shaped sections, the lower ends of said frameworks being spaced from each other, said frameworks being arranged so that the distance between the upper ends of said V-shaped sections is greater than the distance between the lower ends of said frameworks, means including a track extending below said cross member and extending on past said V-shaped sections, a carriage arranged for movement on said track, and block and tackle means secured to said carriage.
2. An arrangement as set forth in claim 1, and means for adjusting the length of said cross member.
3. An arrangement as set forth in claim 1, and means for adjusting the length of each leg of said pairs of frameworks.
4. An arrangement as set forth in claim 1, and means for securing said track to said cross member.
5. An arrangement as set forth in claim 1, and means including at least one clamp for securing said device to the head of a window frame.
